UNITED STATES PATENT OFFICE.

ANDREW J. BARRON, OF CINCINNATI, OHIO, ASSIGNOR, BY MESNE ASSIGNMENTS, TO PHOENIX HORSE SHOE COMPANY, OF NEW YORK, N. Y., A CORPORATION OF ILLINOIS.

SPRING SUSPENSION FOR AUTOMOTIVE VEHICLES.

Application filed December 14, 1922. Serial No. 696,833.

To all whom it may concern:

Be it known that I, ANDREW J. BARRON, residing at Sayler Park Station, Cincinnati, Ohio, a citizen of the United States, have 5 invented certain new and useful Improvements in Spring Suspensions for Automotive Vehicles, of which the following is a specification.

The present invention is a variant of the 10 spring-supporting structure disclosed in my United States Letters-Patent No. 1,432,231, granted October 16, 1922, and the object is to provide an alternative construction more particularly adapted to carrying a heavier 15 load than is feasible with the construction disclosed in my prior patent, aforesaid.

To this end, I have devised a side-spring 20 supporting structure designed to support the load from the axle-casing or housing, and held against tilting by being bolted through the customary perch-hole of the flange of the elongated collar carried laterally by the axle-housing, the supporting-structure embodying a shelf elevated above 25 the said collar-flange and thereby adapted to support the side spring in a position ele- vated above the brake-band housing or drum.

The preferred exemplary construction is 30 disclosed in the accompanying drawing, in which—

Figure 1 is a view in front elevation of my supporting structure, in operative position upon the axle-housing, shown in section; and

Figure 2 is a view in side elevation thereof.

Referring, now, in detail, to the drawing:

1 designates the axle-housing of the rear 40 axle of the automotive vehicle, upon which my supporting-structure is adapted to be supported, the axle-housing or tube being provided, at each end, with an elongated collar 2 secured thereto in usual manner and 45 provided with a lateral flange 3 having the usual perch-hole.

My side-spring supporting structure comprises a horizontal table or shelf 4 and an 50 integral supporting plate 5 right-angularly depending from and preferably coextensive with one longitudinal edge of the shelf, and provided near its lower edge and intermediate the length thereof with an opening registering with the perch-hole in the col-

lar-flange 3. A bolt 6 passes through said 55 registering openings, and a nut 7 is screwed on the threaded end thereof, whereby the supporting-structure is held against tilting on the axle-housing 1.

Connecting the table or shelf 4 and the 60 supporting plate 5 are integral or unitary webs 8, 8, preferably coextensive with the width of said shelf and supporting plate and disposed on each side of the opening in the supporting plate 5.

The webs 8, 8 are extended beyond the 65 lower edge of the supporting plate 5 to provide arms 9, 9 carrying, at their lower ends, a bearing-member 10 having a semi-circular inner surface conforming to the curvature 70 of the axle-housing 1, upon which it rests, and provided with ears 11, 11 apertured to receive bolts 12, 12, which pass through registering openings in similar ears 13, 13 carried by a complementary bearing-member 14. 75 Nuts 15, 15 are screwed on the ends of the bolts 12, 12.

The table or shelf 4, the supporting plate 5, the webs 8, 8, the arms 9, 9, and the bearing-member 10 are all integral, and may be 80 conveniently formed as a casting.

It will be noted that, by my construction, the weight of the load is thrown upon and 85 is directly sustained by the axle-casing 1, the bolt 6 being used merely to keep the structure from tilting.

The elliptical, laminated side spring 16 is 90 secured to the table or shelf 4, preferably by means of bolts 17 projected through holes in the table or shelf and through holes in plates 18, 18 bearing against the upper leaf of the spring, nuts 19 being screwed on the threaded ends of said bolts.

It will be noted that my side-spring supporting structure is designed with a view 95 to extreme simplicity, that it is easily installed in position, and that it is practical from a mechanical and engineering standpoint.

Having thus fully described my invention, 100 what I claim as new and desire to secure by Letters-Patent is:

1. In combination with a leaf spring and an axle housing, a yoke adapted to be clamped to the housing, a horizontal table for supporting the spring, a supporting-plate for said table, right-angularly depending from one side thereof, and unitary webs 105

interconnecting the table and the supporting-plate with the yoke.

2. In combination with a leaf spring and an axle housing, a yoke adapted to be clamped to the housing, a horizontal table for supporting the spring, a supporting-plate for said table, right-angularly depending from one side thereof, unitary webs interconnecting the table and the supporting-plate with the yoke, and means for preventing tilting of the table.

3. In combination with a leaf spring and an axle housing, a yoke adapted to be clamped to the housing, a horizontal table for supporting the spring, a supporting-plate for said table, right-angularly depending from one side thereof, unitary webs interconnecting the table and the support-

ing-plate with the yoke, and means passing through said supporting plate for preventing tilting of the table.

4. In combination with a leaf spring and a flanged axle-housing, a yoke adapted to be frictionally clamped to the axle-housing, a horizontal table for supporting the spring, a supporting-plate for said table, right-angularly depending from one side thereof, unitary webs interconnecting the table and the supporting-plate with the yoke, and means passing through said supporting-plate and the flange of the axle-housing for preventing tilting of the table.

In testimony whereof I hereunto affix my signature.

ANDREW J. BARRON.
